CLAIM

The ornamental design for a display screen or portion thereof with graphical user interface, as shown and described.

DESCRIPTION

FIG. 1 is a face view of a display screen or portion thereof with graphical user interface;

FIG. 2 is a face view of second image thereof;

FIG. 3 is a face view of third image thereof;

FIG. 4 is a face view of fourth image thereof;

FIG. 5 is a face view of fifth image thereof; and,

FIG. 6 is a face view of sixth image thereof.

The appearance of the transitional image sequentially transitions between the images shown in FIGS. 1-6. The process or period in which one image transitions to another image forms no part of the claimed design.

The outer broken lines show the display screen or portion thereof and form no part of the claimed design. The remaining broken lines show text and parts of the graphical user interface that form no part of the claimed design.
